BY Luther Johns ATTORNEY

UNITED STATES PATENT OFFICE

GEORGE W. DIENER, OF OAK PARK, ILLINOIS

BLOWTORCH

Application filed March 26, 1928. Serial No. 264,695.

These improvements relate to blow torches of the kind in which a preheating of certain parts is required for generating combustible gas from the liquid fuel for starting the 5 working flame.

The chief object of the invention is to provide a construction in which this preliminary generation of gas is accomplished in peculiarly short space of time, with what is probably 10 a minimum amount of fuel consumed, and with a certainty and effectiveness unusual in such devices prior to my present invention.

It has been appreciated heretofore that 15 high winds and cold weather militate against the successful starting of such torches, and various suggestions have been made to overcome this disadvantage by the provision of covering devices for various parts of the 20 apparatus. That disadvantage, which is quite substantial, is entirely overcome according to these improvements with respect to the torch parts involved in the initial generation of gas, and the present invention in that 25 respect is a very notable improvement over all that I am acquainted with suggested heretofore for such purpose. That feature, however, is somewhat incidental, although important, for the present invention is not so 30 much primarily directed to protection from outside influences, as wind, rain, sleet, etc., as it is to means providing a better preheating unit or device, namely, means by which a very intense heat is developed, and rapidly—the 35 provision of something in the nature of a furnace wherein not only an unusually intense heat is produced, considering the character of the device, but one in which that heat is conserved and so directed that the gas generation 40 for working operations is brought about in unusually large volume and in an unusually brief space of time.

Turning to the drawings forming a part 45 hereof, Fig. 1 shows a conventional blow torch having these improvements in the form of an attachment or addition operatively applied thereto, parts being broken away; Fig. 2 is a top view of the device of Fig. 1; Fig. 3 is a front end view of the same; and Fig. 4 is 50 a perspective of the housing member.

The blow torch illustrated, apart from the housing member, may be considered to be of a well-known kind and construction. It is sufficient to point out that the drip pan 10 contains non-combustible fibrous material 11, 55 such as asbestos; that there is a pump mechanism 12 by which some of the fuel, as gasoline or kerosene, may be forced initially into the flame pan, usually called a drip pan; and that after the gas initially generated is ignited a 60 regulable flame issues through the barrel 13. The object of the flame in the flame pan is to heat the metallic parts below the barrel 11 to such an extent as to volatilize fuel in the feed duct contained in those parts, all as is well 65 understood.

The housing 15 of Fig. 4 is shown as being of thin sheet metal having a narrow saddle part 16 at the top with a hole therein through which extends the threaded end of the stem 70 17 of the soldering-iron-holder 17^a. This saddle-like part 16 conforms to the upper half of the cylindrical barrel 13, and the two oppositely-disposed front edges 18 of the housing 15 follow around the barrel 13 somewhat, extend forward and terminate in the vertical abutting edges 19 of the front wall 23. 75

Figs. 1 and 3 show that at 20 the housing is open to a small extent below the barrel 13. This is in front of the cylindrical cast metal 80 part 21 forming part of the head, and the opening at 20 provides for draft at this place and insures the development of a strong flame around the front side of the upright part 21 containing part of the fuel feed duct. 85

The two oppositely-disposed edges 22 of the housing 15 conform fairly snugly to the shape of the parts of the head immediately adjacent thereto. At 22^a these rear edges are shown by dotted lines in Fig. 3 as being 90 spaced slightly from each other, forming a narrow opening into the hollow interior of the casing. Such an opening is not essential, but it provides a convenient means for applying a match to light the fuel in the drip 95 pan.

The housing walls are shown as having the general contour of the drip pan in horizontal view and the housing walls enter the drip pan 10 and fit therein snugly close to the edges 100

thereof. When held by the screw at 17 the housing is strongly secured in its desired position, but it may be readily removed by simply removing the screw and then raising the 5 rear end of the housing at 22^a and slipping it off of the barrel. The sheet-metal formation enables the sides to be sprung apart for this purpose if necessary in a given construction.

Attention is now called to the several openings as 25, 25^a and 25^b through the side walls 10 15^a of the housing a short distance above the drip pan. Another opening 26 in each side wall 15^a is positioned approximately on a line with the bottom of the barrel 13. While the 15 arrangement of these holes as 25, 25^a, 25^b and 26 may vary, and while I do not desire to be limited to the particular number of such openings, or any particular openings for intake and output, I have found from experimentation that the number, arrangement and proportions substantially as illustrated provide the desired results in the particular form 20 of device shown. In my practice the openings 25, 25^a, 25^b and 26 are severally three- 25 sixteenths of an inch in diameter.

The openings 25, 25^a and 25^b are for intake of air to feed the flame in the drip pan. These openings are therefore so positioned as to feed air closely adjacent to where the flame 30 starts. They are arranged at various places along the drip pan so as to supply oxygen to the flame readily at all places where combustion is taking place. Some air enters at the small opening between the edges 22^a and 35 that supply is sufficient for the immediate rear end portion of the drip pan, and that supply taken with that through the two oppositely-disposed openings 25 is sufficient to supply say the rear half of the flame in the 40 drip pan. The holes 25^a and 25^b are somewhat closer together and supply air for the flame in the more-closed end, namely the front end, of the housing. The oppositely-disposed upper openings 26 are outlets. 45 Some outlet is provided along the edges 22, as is preferably the case to a small extent, so as to carry the flame into immediate association with the metal parts of the head. The outlet at 20 has already herein been referred 50 to.

Now when fuel is saturating the material 11 in the drip pan and it is lighted, the flame is in a typical combustion chamber, and the combustion has very much the character of 55 that in a furnace. The fuel burns with a blue flame denoting perfect or substantially perfect combustion. The flame is very much like that of a Bunsen burner. Instead of having merely a body of flickering red flame 60 as in the older practice rising slowly under the influence of the lower specific gravity of its heated particles we have here a stream of blue and hot flame moving more rapidly upward, and this flame is directed immediately 65 to and upon the parts to be preheated, and,

furthermore, since the housing encompasses the flame in the flame pan and the parts to be preheated a considerable amount of heat over and above that of the current flame itself is built up through the conservation of heat by 70 the housing.

So far as I am aware the provision of confining walls with air intake and outlet provisions and forming a combustion chamber for the preheating device or parts of such blow torches is wholly new, and its results are in 75 very marked contrast to those previously known.

Since various changes and modifications may be made from what is thus specifically illustrated and described without departing from the spirit and essence of the invention thus set forth, I contemplate as being included in the present invention all such changes and departures as fall within the scope of the 80 appended claims.

I claim:

1. A blow torch of the character described having a flame barrel and a preheating system comprising gas generating parts, a flame pan for preheating those parts, and a housing substantially surrounding the flame area of the flame pan and substantially closely encompassing the gas generating parts and portions of the flame barrel adjacent thereto to form a combustion chamber, there being means for conducting air into direct association with the flame at various places closely adjacent to the flame pan, together with outlet openings for conducting products of combustion from the upper portion of the hollow interior of the housing. 95

2. In a blowtorch of the character described having gas generating parts and a drip pan below said parts for preheating them, the combination therewith of a housing substantially surrounding the flame area of the drip pan, extending into the drip pan and being supported thereby and encompassing substantially closely the gas generating parts, with air intake openings at spaced-apart places in said housing adjacent to the drip pan, and outlet openings providing for the escape of products of combustion from the upper portion of the hollow interior of the housing. 105

3. In a blow torch of the character described having a flame barrel, gas generating parts, and a drip pan below said parts for preheating them, the combination therewith of sheet-metal housing having a narrow saddle-like part substantially fitting upon the upper surface of the flame barrel, extending downward therefrom to form side walls, and said side walls extending into direct association with the drip pan, said housing substantially closely fitting upon said barrel and the gas generating parts at the upper part of the housing and substantially surrounding 110 115 120 125 130

the flame area of the drip pan and forming a combustion chamber, with air-intake openings in the housing adjacent to the drip pan, and with outlet openings leading from the 5 upper portion of the hollow interior of the housing.

4. In a blow torch of the character described having a flame barrel, gas generating parts and a drip pan below said parts for pre-heating them, the combination therewith of a 10 housing member held at its lower edge portions within marginal edges of the drip pan and substantially encompassing the flame area thereof and extending upward and encompassing said gas generating parts with a 15 substantially close fit and passing over the top of said barrel, with means at the top of said barrel for holding the housing member rigidly yet releasably in its normal position for 20 use, said housing member having spaced-apart air intake openings respectively at a short distance above the upper edge of the drip pan and having outlet openings leading from upper portions of the hollow interior 25 of the casing.
